Primary Examiner — T. Chase Nelson*Assistant Examiner* — John Windmuller(74) *Attorney, Agent, or Firm* — Curtis L. Harrington; Kathy E. Harrington; Harrington & Harrington(57) **CLAIM**

The ornamental design for a wire grip, as shown and described.

DESCRIPTION

FIG. 1 is a front view;

FIG. 2 is a rear view;

FIG. 3 is right side view;

FIG. 4 is a left side view;

FIG. 5 is a top view;

FIG. 6 is a bottom view; and,

FIG. 7 is a front plan view showing the wire grip in a position engaging a wire structure when pulled by a hook structure, the wire structure and the hooked structure shown in dashed line format and forming no part of the invention hereof.
